PORTABLE SANDING MACHINE

Allan B. Walker, Piedmont, and Harry J. Riddle,
Alameda, Calif.; said Walker assignor to said
Riddle

Application November 2, 1949, Serial No. 124,958

1 Claim. (Cl. 51—170)

1

The invention relates to sanding machines of the portable, power-driven type, utilizing one or more reciprocally driven sanding shoes and adapted for sanding or other finishing operations on furniture, floors, woodwork, or the like.

An object of the present invention is to provide in a portable sanding or finishing device of the character described a powerful, ruggedly constructed, high-speed machine, having an improved, symmetrically-balanced arrangement and construction of the parts making up the drive assembly, permitting the use and application of greater power for the size of the unit and with large factors of safety in the design affording heavy duty and long-continued operation of the machine.

Another object of the invention is to provide a machine of the character described having a pair of reciprocating sanding shoes driven in an out-of-phase, opposed and balanced relation, thereby permitting the machine to be easily handled and precisely manipulated over the work to be sanded, with minimum effort.

A further object of the invention is to provide a sanding machine of the character described embodying an improved universal support for the sanding shoes, thus enabling the sanding or finishing of work having other than a flat surface and at the same time effectively preventing any tendency of the leading edges of the shoes to tip or bite into the surface being worked.

Still another object of the invention is to provide a sanding machine of the character above having an improved sanding pattern permitting the sanding or finishing operation to be carried into corners and to the wall edges of floors and the like.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claim.

Referring to said drawings:

Figure 1 is a side elevation, shown partly in cross section, of a sanding machine constructed in accordance with the present invention.

Figure 2 is a plan sectional view taken substantially on the plane of line 2—2 of Figure 1.

Figure 3 is a plan sectional view taken substan-

2

tially on the plane of line 3—3 of Figure 1 and shown on a somewhat enlarged scale.

Figure 4 is an end elevation of the machine with a portion shown in cross section, taken on the plane of line 4—4 of Figure 1, the scale being slightly enlarged with respect to Figure 1.

Figure 5 is a cross-sectional view of the machine on the same scale as Figure 4 and taken substantially on the plane of line 5—5 of Figure 1.

Figure 6 is a further enlarged sectional view taken substantially on the plane of line 6—6 of Figure 3.

Figure 7 is a cross-sectional view taken substantially on the plane of line 7—7 of Figure 6.

Figure 8 is a cross-sectional view taken substantially on the plane of line 8—8 of Figure 6.

The sanding machine of the present invention and as depicted in the accompanying drawing consists in an integral assembly including an electric motor 11, a casing 12 for the drive assembly, and a pair of shoes 13 and 14 mounted in underlying relation to the casing 12 and supported and driven for reciprocation. The casing 12 is here provided with top wall 16 and depending side walls 17 and 18, and end walls 19 and 21, forming a continuous depending skirt around the top wall 16. The casing is preferably of substantially rectangular form as viewed in plan, see Figure 2, and the front and rear ends of the casing may be rounded for appearance as illustrated in Figure 1. A gear housing 22 is secured within the casing to the under side of the top wall 16 and as here shown projects up through a central opening provided in the top wall for securing thereto a cover plate 23, the latter preferably overlying the periphery of the opening in the top wall so as to clamp the top wall, as shown in Figures 1 and 4, between a depending flange 24 on the cover and an annular shoulder 26 on the gear housing. The electric motor 11 is set in a vertical operating position and the lower end of the motor case is preferably recessed to fit around and upon the periphery of the cover plate 23 and upon the upper side of the casing 12. The motor casing and gear housing assembly is here unitarily secured together by means of through bolts 27 and 28, which extend from the under side of the gear housing, through the gear housing and cover plate 23, and up through the length of the motor housing through the motor stator 29, and are threadably attached at their upper ends in end portions 31 and 32 of handles 33 and 34.

As will be noted from Figure 1, handles 33 and 34 are positioned vertically on opposite sides of the motor and are attached at their lower ends to

3

the opposite end walls 19 and 21 of the casing and curved inwardly at the upper ends 31 and 32 for insertion through opposed openings in the motor housing for attachment to the upper ends of the through bolts 27 and 28. Preferably, additional bolts 30 are used for fastening the cover plate 23 to the gear housing and thereby securely clamping the gear housing to the casing 12.

As an important feature of the above described construction, the cover plate 23 for the gear housing also forms a lower end wall for the electric motor and is desirably fitted with a bearing 36 for journaling the lower end 37 of the motor shaft 38, the shaft end 37, as here shown, projecting through the bearing 36 and into a gear chamber 39 provided in the housing 22. Preferably, a conventional air propelling fan 41 is secured on the motor shaft 38 between the bearing 36 and the rotor 42 of the electric motor, air circulation being provided through the motor between air slots 43 (see Figure 4) and 44 (see Figure 1). As will be noted from Figure 1, the handles 33 and 34 are spaced from the motor housing to permit easy gripping in the hands of the user, and an electric switch 45 may be attached to one of the handles as here shown for convenient turning on and off of the electric motor.

The gear chamber 39, above noted, here opens to the top of the housing 22 and is closed off and sealed from the motor by the cover plate 23. The chamber has a sufficient width and depth to accommodate a centrally arranged worm gear 47 secured on the shaft end 37, and worm pinions 48 and 49 enmeshed therewith and positioned on opposite sides of the worm gear 47, the pinions 48 and 49 being mounted on driven shafts 51 and 52 for rotation about horizontal axes and with the gears mounted in a substantially common vertical plane extending transversely across the gear housing. With reference to Figure 2, it will be noted that the driven shafts 51 and 52 are journalled in the gear housing 22 for rotation about transversely spaced parallel horizontal axes on opposite sides of and extending perpendicular to the drive shaft 37. Shaft 52 is journalled in bearings 53 and 54 mounted in the opposite sides of the gear housing, and projects from the outer side of the gear housing and into the interior of casing 12 adjacent end wall 21, and has affixed to its outer end portion 56, for rotation therewith, a cam 57. In a similar manner, shaft 51 is journalled in bearings 58 and 59 in the opposite sides of the gear housing and projects from the gear housing into the interior of casing 12 adjacent end 19, where the outer projecting shaft end 61 is fitted with a cam 62. With further reference to Figures 2, 4 and 5, it will be noted that worm pinions 48 and 49 are splined to their respective shafts 51 and 52 and cams 57 and 62 are keyed to their respective shaft ends 56 and 61. If desired and as here shown, the pinions 48 and 49 may be held in central position within the chamber 39 and in proper engagement with the worm gear 47, by sleeves 63, 64, 66 and 67 mounted on shafts 51 and 52 on opposite sides of pinions 48 and 49 and extending into abutting relation with the adjacent shaft bearings.

A pair of slide members 73 and 74 are connected to the cams 57 and 62 by cam followers 76 and 77 and are, in turn, connected to the shoes 13 and 14, so that the rotary motion of the driven shafts 51 and 52 as translated by the cams into a horizontal reciprocating motion is transmitted to the slide members and the shoes. The preferred construction of the slide members and shoe

4

connection is best illustrated in Figure 5. With reference to this figure it will be noted that there are positioned along the length of casing 12 on the opposite side walls 17 and 18 a pair of elongated guide ways 78 and 79 which slidably support for reciprocation the slide members 73 and 74. The guide ways 78 and 79 may be formed, as here illustrated, of elongated channels 81 and 82 which contain blocks 83 and 84 of suitable material, having key ways 86 and 87 formed in their opposed faces, the channels and blocks being secured on the side walls of the casing by dowel screws 88 and 89, see Figure 4. The slide member 74 is provided with laterally extending keys 91 and 92 which are slidably received in the key ways 86 and 87. The guide blocks 83 and 84 and keys 91 and 92 are preferably formed of very hard, wear resistant material, having a low coefficient of friction. Certain steel alloys and others such as tungsten carbide or stellite are suitable for this purpose.

The blocks 83 and 84 may be welded or brazed in the channels 81 and 82 and the keys 91 and 92 may be similarly secured in the body of the slide member, as shown in Figure 5.

The slide members 73 and 74 are formed with upstanding arms or bosses 96 which support adjacent their upper ends transversely extending pins 97 (see Figure 5). The cam followers 76 and 77 are here in the form of rollers journalled on the pins 97 and are supported thereby in fluted recesses 98 formed in the periphery of cams 57 and 62. These fluted recesses have a longitudinal undulation so that upon rotation of the cams a longitudinal reciprocation is imparted to the cam followers.

One of the important features of the present invention is the manner of attachment of the shoes 13 and 14 to the slide members, wherein a desired close coupled driving force is imparted to the shoes while a limited universal movement of the shoes relative to the slide members is permitted. This construction is best illustrated in Figures 5 and 6 of the drawings wherein it will be noted that there is provided under the open side of the casing 12 a bottom pan 99 which completely covers the under side of the casing but is provided with a pair of elongated openings 101 and 102, see Figures 1 and 6, to accommodate the driving connection extending from the slide members to the shoes. Any suitable means may be used for securing the bottom pan to the casing, and as here shown in Figure 1 the pan is formed with a plurality of up-set lugs or pins 103 which slidably fit the interior of the casing side walls. Means is provided for sealing off the openings 101 and 102 so as to effectively shut out from the drive mechanism abrasives, dust, and the like. As here shown, such means includes sealer plates 104 and 106 which are carried with the shoe connection and are provided with an upstanding peripheral flange 107, see Figures 5 and 6, containing within the flange an O sealing ring 108 which is compressed between the plates 104 and 106 and the under side of the bottom pan 99.

The shoes 13 and 14 are of generally rectangular construction having a width completely underlying the unit as shown in Figure 5 and a combined length covering the majority of the length of the unit, see Figure 1, and are subjected to a reciprocating movement extending to and slightly beyond the opposite ends of the unit, so that the sanding pattern afforded completely covers and overlaps the transverse and longitudinal dimensions of the unit. Also, the shoes are constructed

in a manner permitting the easy renewal of the sand paper or polishing cloths or the like. As will be best seen from Figures 5 to 8 of the drawings, the shoes are here composed of a plurality of superimposed plates 109, 111 and 112. The lowermost plate 109 is formed with upstanding flanges 113 and 114 at its opposite ends, which extend upwardly from plate 109 in horizontally-spaced relation to upstanding flanges 116 and 117 on plate 111, so as to define channels 118 and 119 therebetween, the plates being preferably integrally secured together as by spot welding or the like. The uppermost plate 112 is locked to plate 111 by a return gripping flange provided at the upper extremities of the flanges 116 and 117.

A post assembly is used to connect the shoes to the slide members and also to carry with it the sealing plates 104 and 106. This construction is best detailed in Figures 5 and 6 wherein it will be noted that the sealing plate 104 is provided with a centrally arranged depending spherical boss 121 which is received in a spherical recess 122 formed in the top plate 112 of the shoe by a general elevation of the central portion of the plate 112 from the intermediate shoe plate 111. A post or pin 123 extends centrally through the ball and socket connection provided by the boss 121 and recess 122, and is the main connecting element of the assembly. As will be noted, this post is provided with an enlarged head 124 underlying and fixed to the recess portion of plate 112, and extends centrally through this recess and through a centrally arranged opening 126 in the boss 121. The upper end 127 of the post extends through an opening 128 provided in an inverted cup 129, the post being held against retraction by a cross pin 131 carried by the post end 127 and locked over the periphery of the opening 128 in the cup member. Preferably, as seen in Figures 5 and 6, a bayonet-type of connection is used for this post end so as to permit its removal when desired.

As an important feature of the present construction, resilient means is employed in the operating connection between each of the shoes and the slide member, so as to constantly urge the shoes to assume a horizontal position parallel to the slide members and to resiliently resist movement from such position. As here shown, such resilient means is in the form of compressible pads 132 carried in the inverted cup member 129 in surrounding relation to the post 123 and maintained under pressure by an underlying supporting member 133 also surrounding the post 123 and having a spherical boss 134 fitting into the interior concavity of boss 121. The pad 132 may be of any suitable compressible, resilient material, such as rubber or similar material. Desirably, the dimensions of the respective parts in the post assembly are such as to normally place the pad 132 under some compression, thereby urging the shoe into a position parallel to the sealing plate 104 and the slide member. As above noted, however, the shoe is permitted a limited universal movement effected by the sliding contact of the boss 121 in the recess 122 within the limits of opening 126. Such a swinging movement of the post, of course, places the pad 132 under further compression, which thereby resiliently urges the shoe to return to its horizontal position. While the post assembly as above described affords limited universal action of the shoe, rotation of the shoe about the axis of the post assembly is prevented by holding against ro-

tation the inverted cup 129, the pad 132, the supporting member 133, and the sealing plate 104, by the provision of one or more flats 136 (see Figure 3) on the post 123 engaging with flats provided in the post-receiving openings in members 133, 132 and 129. As will be seen from Figure 5, the sealing plate 104 (applicable also to the other sealing plate 106 and its assembly) is anchored to the slide member 74 by bolts 137 and 139 which extend through apertures in the plate 104 and are threaded into slide member 74. As will be noted in comparing Figure 5 with Figure 6, the cup member 129, pad 132 and underlying supporting member 133 are all of rectangular form, that is, having a greater dimension longitudinally of the machine than width-wise, and these members are contained within an elongated recess 139 in the slide member 74. In this manner, members 129, 132 and 134 are supported by the slide member against relative rotation and they, in turn, by reason of the post flat 136 and the anchoring of the post head 124 to the shoe, prevent rotation of the shoe.

As above noted, means is provided in the present construction for quick and easy changing of the sandpaper or other sheets of abrasive or polishing material which may be used with the machine. With reference to Figures 5 to 8, it will be noted that there are provided in the channels 118 and 119, hereinabove described in connection with the shoes, locking rollers 141 and 142. These are of elongated form, as seen in Figure 7, and of oval cross-section as viewed in Figure 6, and have a transverse dimension sufficient, upon appropriate rotation, to bind against the adjacent side walls of the channel. These rollers are supported within the channels for rotation by underlying clip members 143 and 144, which have raised bearing portions 146 and 147 at their opposite ends for journaling reduced end portions 148 and 149 of the rollers. The latter end portions may be of rectangular or polygonal form so as to fit within a key or the like which may be used for appropriate turning of the rollers. A sheet 151 of sandpaper, emery cloth, or buffering or polishing material is supported at the under side of bottom plate 109, preferably on a suitable compressible pad 152. The latter may be of any appropriate material such as felt or the like. The opposite ends of the sheet 151 are wrapped around the exterior of the shoe flanges 113 and 114 and extended into channels 118 and 119, where upon appropriate rotation of the rollers 141 and 142 the sheet ends are clamped against the shoe flanges 116 and 117. Preferably, flanges 113 and 114 extend inwardly as shown in Figure 6, so as to overhang the rollers 141 and 142 to thereby assist in retaining these rollers in the channels. The rotation of the rollers 141 and 142 to clamp the ends of the sheet 151 as above described also tends to draw the sheet tightly around the bottom of the shoe, as noted.

Means is also provided for detachably securing the shoes 13 and 14 to their respective mountings so as to permit the renewal of the shoes or change of the type or size of the shoes. As above described, the flanges 116 and 117 of the shoe plate 111 are turned inwardly at their upper end so as to overlie the side edges of plate 112. In this manner, flanges 116 and 117 form side channels for slidably receiving the opposite edges of plate 112. A detent means as illustrated in Figures 3, 6 and 8 is used for holding the shoe plate 111 in proper position upon the carrying plate 75 112. As illustrated, an elongated, flat spring

member 155 is secured at one end, as by rivet 153, to the upper side of plate 112, across the forward extremity of this plate. The opposite end 150 of the spring member 155 is extended transversely across to the opposite side of plate 112, where it is manually engageable for elevation against the resilient resistance of the spring member to deflection. Carried centrally of the spring member 155 is a detent button 154 which extends through a registering opening 156 in plate 112 and into an aligned opening 157 extending through plates 109 and 111. To disengage the shoe from the carrying plate 112, the outer end 150 of the spring member is raised so as to elevate the detent button 154 from its engagement in opening 157, after which the shoe may be slid transversely away from the side edges of plate 112. To apply the shoe, the side shoe channels provided by flanges 116 and 117 are aligned with the opposite side edges of plate 112 and the shoe slid transversely upon the plate until the detent button 154 snaps into the shoe plate opening 157, which locks the shoe in position.

As will be noted from the foregoing, the machine is so designed as to fall entirely within a vertical projection of the outer limits of its sanding operation, and consequently the machine can be worked into corners or any space which will contain it. In other words, a full and complete sanding pattern completely underlies the machine. If desired, a bumper strip 158 of rubber or the like may be provided around the base of the casing for facilitating movement of the machine into corners and against walls, etc. It will also be noted that the drive mechanism above described provides an out-of-phase movement of the shoes 13 and 14, so that these shoes are always moved toward or away from each other. In other words, while shoe 13 is moving to the left as viewed in Figure 1, shoe 14 will move to the right, and contrariwise, when shoe 13 moves to the right shoe 14 moves to the left. In this manner, the reacting forces from the shoes to the machine are always opposed and substantially equalized, thereby permitting easy handling and manipulation of the machine without tendency of the machine to "walk" on the surface being worked. The feature of dynamic balance is also generally carried through in the drive and driven parts by reason of the general symmetry of the driven parts about the drive shaft 38. The drive mechanism here used also affords the use and application of relatively high horse power in a machine of limited size. In this connection it will be noted that the main drive forces of the machine and all stresses resulting from either reciprocating or shock strains are contained entirely within the gear casing assembly, and its cover plate 23, which may be ruggedly constructed with ample factor of safety to withstand these forces. Also, provision is made for complete lubrication of the gear train including the worm 47 and pinions 48 and 49, in that the gear chamber 39 is completely sealed and is desirably filled with a suitable lubricant. A drain plug 159 is preferably provided in the bottom of the gear

chamber for periodic removal of the lubricant.

It will now be clear that the machine of the present invention is ruggedly constructed for powerful, high-speed operation and for long continued usage with minimum attention or repair. At the same time, the machine may be readily handled over all types and contours of surfaces, the swivel action of the shoes providing an automatic accommodation to other than flat surfaces and allowing the operator to rock the body of the machine over to one side or the other to clear side obstructions while leaving the shoe flat on the surface. While such universal mounting of the shoes is provided, as above described, the driving force is applied to the shoes very close to the sanding surface, so that maximum utilization of the applied force is obtained without undue stress on any of the connecting parts. Also, the resistance to swiveling action of the shoe is controlled by the resilient pads in the post assembly above described, and if desired pads of different stiffness may be used with the machine for obtaining desired sanding characteristics. For example, stiffer blocks tend to sand out the surface being worked to a plane surface. Pads of different characteristics may be readily inserted by disassembling the shoe connection as above described.

We claim:

A sanding machine comprising, a casing, power driven reciprocating means in said casing, a sealing plate slidably mounted on the under side of said casing for reciprocation, a sanding shoe, said plate and shoe being formed with interfitting ball-and-socket portions supporting limited universal action, a post member secured to said shoe and extending through said ball-and-socket portions and connected to said first means for reciprocation of said plate and shoe, and a resilient pad carried by said post member and resiliently resisting displacement of said shoe away from a position substantially parallel to said plate.

ALLAN B. WALKER.
HARRY J. RIDDELL.
